UNITED STATES PATENT OFFICE.

CHESTER C. LYMAN, OF CLEVELAND, OHIO.

STEAM-DERRICK.

SPECIFICATION forming part of Letters Patent No. 294,395, dated March 4, 1884.

Application filed September 14, 1883. (No model.)

To all whom it may concern.

Be it known that I, CHESTER C. LYMAN, of Cleveland, in the county of Cuyahoga and State of Ohio, have invented certain new and useful 5 Improvements in Steam Hoisting-Derricks; and I hereby declare the following to be a full, clear, and exact description of the invention, such as will enable others skilled in the art to which it pertains to make and use it, reference 10 being had to the accompanying drawings, which form part of this specification.

My invention relates to improvements in steam-derricks; and it consists, first, in mounting the steam mechanism for operating the 15 derrick upon a revolving platform adapted to make a complete revolution or any part thereof; also, in locating upon said platform a frictional gear mechanism for raising, holding, and lowering the outer end of a boom-arm 20 whose opposite end is securely hinged to the rotary platform; also, in locating a series of anti-friction rollers underneath said revolving platform, which in a great degree carry not only the platform and its machinery, 25 but also the boom and its load; also, in supporting the center of said platform upon an adjustable step by means of a vertical journal resting thereon, as hereinafter more fully described; also, in providing suitable anchorage, 30 with braces, rods, and nuts, for the purpose of holding and governing said step in its vertical position; also, in locating the safety-roller underneath the flange in such a manner as to prevent the upper platform from tilting without 35 raising the base below; also, in providing and locating the combination of braces, whose lower ends rest upon and against the inner sides of the truck-frame, and are held from spreading by the longitudinal rods passing 40 through the sides of said base, both lengthwise and crosswise, and the top or upper end of said braces being firmly united with the hub, thereby forming a firm seat or bearing for the suspended step below, and also a firm bush- 45 ing through which the step-journal passes and is kept in its vertical and central position, and thereby becoming the center axis of the platform motion; also, in providing one or more of the truck-wheels with a tooth-flange, into 50 which are geared one or more cog-wheels operated by a crank to cause the derrick to be moved along its track.

In the drawings, Figure 1 represents a side elevation of my improved derrick. Fig. 2 is a detailed sectional view, showing the construction of the segment and roller. Fig. 3 represents a longitudinal vertical section of Fig. 1. Fig. 4 is a section taken through the line *xx* in Fig. 3.

In Fig. 1, *M* are anti-friction rollers adapted 60 to travel on a circular track, *L'*, and are propelled thereon by pressure of the upper circular bearing, *L*, resting thereon; hence it is apparent that the said rollers *M* travel only one-half the distance of the platform which propels 65 them, which, when taken together with their being anti-friction in their movement, plainly shows a great saving of power over wheels acting on an axle, and also a saving of wear on the tracks.

O denotes absence of the outer band, which, when in its place, serves to keep the said rollers in proper place and equidistant from each other.

E' is the driving-pinion secured to the upper 75 platform, and meshes into the circular stationary rack resting upon the base below, whereby the platform, by turning of the pinion, is caused to revolve in either direction by use of the lever in hands of the operator.

I' is a truck-wheel whose flange is composed 80 of cog-teeth, into which are geared a series of compound cog-wheels, as shown at *I² I³ I⁴*, and governed by a crank, causing the derrick to move along its track *J*.

In Fig. 2, *L'* is the roller-track, the outer edge of which forms also the segment circular rack, into which meshes the pinion *E'*, and the under side of said rack is also provided with a circular horizontal flange, under which is located the safety-roller *P* in such a manner as to prevent the platform from rising without lifting the truck-frame below. The roller *P* is secured to the upper platform by the braces *h*, as shown, and is thus loosely carried around, 90 and is not intended to roll against its track, except when the derrick is overloaded, or in case of receiving a foul hitch, as is sometimes the case when raising its load up through the hatch of a vessel.

In Fig. 3, *R R* represent two sides of the truck-frame, which is secured against spreading by the use of longitudinal rods, (shown at *Q*.)

I I are braces resting upon and against the sides of truck-frame R R, and their upper ends against the hollow hub G², and thus form a firm support for the hub-collar H', said collar serving a twofold purpose: first, a support for the adjustable step-rod g', and, secondly, as a guide for the rim H, which acts, in conjunction with the band o, in keeping the rollers M upon the track in uniform position.

10 The top of platform central bearing is shown at G resting upon an adjustable step, G², the journal end of which passes through the hub G², and is thereby kept in a vertical position, thus not only forming a support to center of 15 platform, but also becomes the axis or center of motion to the platform. The step g, by use of its rods and nuts, may carry a greater or less portion of the weight resting upon the platform, and is also useful in compensating for 20 wear of the various parts and in keeping the machinery in line, especially that part located near the platform center.

G' denotes lower end of the vertical journal resting upon the step, having its lower end 25 separate from the main journal, whereby it may be cast on a "chill"—that is, cast hard—while the upper portion, being separately cast, may be softer, capable of being turned with a tool to fit the hub through which it passes.

30 D is one of two wheels between which is a chain-drum, used for raising or lowering a bucket, as shown in the drawings, and also in Patent No. 222,142, granted me December 2, 1879, which is not here claimed; but I am not 35 aware that a frictional gear mechanism has ever been shown in a revolving derrick for raising, holding, and lowering the end of a boom-arm, as shown.

F denotes one of two wheels between which 40 is located a drum, around which passes a chain, thence around a series of chain-blocks, and to the boom-arm, as shown in the drawings.

E represents one of two friction-collars secured to the driving-shaft. The friction-wheels 45 F, together with their drum, are made fast to the shaft on which they revolve, said shaft being journaled in an eccentric boxing governed by one or more levers.

f is a lever, which, when thrown in one direction, causes the wheels F to press against the driving friction-wheels E, thereby winding 50 the chain, thus causing the boom to rise, so as, when swung, to clear any obstruction in its passage. Then by a quick reverse movement 55 of the lever f the wheels F are disengaged from the driving-wheels E, and at the same instant forced against the brake-shoes F² with sufficient force to hold the boom until swung past the obstructions, as mentioned, and to 60 place of depositing its load. Then by a gen-

tle pressure on the lever f the wheels F are allowed to slip or slide against the brake-shoes F² until the boom is lowered to come in line with the hatch or other place of deposit, and there held by means of the lever until the 65 bucket or load is caused to descend by means of the lifting-drum (located at the right of the drive-shaft) sliding against the brake-shoes, until place of depositing the load is reached, after which, by a reverse movement of the 70 hand-lever, the frictional contact with the said brake-shoes is broken, and at the same instant said drum-wheels are forced against the driving friction-collars, thereby causing the drum to revolve, winding the chain or rope attached 75 to the bucket, which, when sufficiently elevated, is stopped and securely held by a reverse movement of the hand-lever, causing the lifting frictional contact to be broken and the lifting-wheels to be forced against the brake- 80 shoes with sufficient force to hold the bucket at any point within its range. The elements of the combination for manipulating the bucket are quite similar to those for raising and lowering the boom, and are each driven by the 85 same friction-collars. At the same time their movements are independent of each other and for a separate purpose—namely, the combination on the left for governing the sweep of the boom, and the other, situated at the right, 90 governs the raising, holding, or lowering of the bucket f until the bucket or load descends. Thus it will be seen that the object of this last-named device is to lengthen or shorten the 95 sweep of a boom-arm, which by this frictional gearing can be accomplished safely and more rapidly than by any other method known to the inventor.

Having thus described my invention, what I claim is—

1. A revolving derrick, a double friction-gear mechanism, and brake-shoes, in combination with the mast-blocks and ropes and the boom-arm, for the purpose of raising, holding, and lowering said boom-arm, substantially as 105 and for the purpose described.

2. In a steam-derrick, the braces I I, in combination with hub G² and flange H', substantially as and for the purpose set forth.

3. The circular collar H, in combination 110 with the hub G², substantially as shown and described.

4. The adjustable step G² and rods and nuts g', in combination with the step-journal, substantially as and for the purposes described. 115
